UNITED STATES PATENT OFFICE.

HUGO JUNKERS, OF AACHEN, GERMANY, ASSIGNEE, BY MESNE ASSIGNMENTS, TO L. M. WHEELOCK, OF BOSTON, MASSACHUSETTS.

PISTON FOR INTERNAL-COMBUSTION ENGINES.

1,320,064.

Specification of Letters Patent.

Patented Oct. 28, 1919.

Application filed September 15, 1914, Serial No. 861,919. Renewed August 13, 1919. Serial No. 317,379.

To all whom it may concern:

Be it known that I, HUGO JUNKERS, a subject of the German Emperor, residing at Aachen, Germany, have invented certain new and useful Improvements in Pistons for Internal-Combustion Engines, of which the following is a specification.

This invention relates to pistons for internal combustion engines. The object of 10 the invention is to provide an improved construction for the piston of such an engine whereby the head of the piston is enabled to expand freely with changes of temperature and whereby loss of heat due to the carrying away of heat by the piston is greatly reduced.

In accordance with the invention, I provide upon the end of the piston a multiplicity of narrow grooves distributed over 20 the end of the piston which is exposed to the combustible gases, there being preferably as many grooves as is possible in order that the surface portion of the piston which is heated most severely can expand freely and the 25 grooves being very narrow so that very little heat will be conducted away therein. In some instances, when the construction is such that the end of the piston is subjected to greater heat over one part thereof than 30 over another, I find it desirable to provide a greater number of grooves over that part of the piston which is most severely heated. In certain cases the grooves require to be of only such a width that the individual parts 35 bounding them can expand freely and independently of one another. This may be a fraction of a millimeter. No current of gas which enters into such narrow grooves can eddy in them, so that no material losses of 40 heat can arise in the grooves. In addition, owing to the relatively small width and great depth of the grooves they become filled with the residues of combustion when the engine is working, which residues exercise 45 an insulating action without preventing expansion. If desired, the grooves may be enlarged toward the interior of the piston so that the residues of combustion are prevented from falling out of them. Instead of 50 employing the residues as insulation, the grooves may be provided from the first with an insulating material or the insulating material may be cast into the piston head.

As mentioned above, the grooves should 55 be most numerous where the head of the pis-

ton is heated most highly by the fuel. For example, if the fuel is injected toward the middle of the piston most grooves should be in the middle. On the other hand, if the fuel is injected parallel to the head of the 60 piston, as is the case for example in twin piston engines in which the jet of fuel does not contact at all with the piston but spreads out during the combustion like a fan in front of the piston, in consequence of the approximately uniform heat over the surface of the 65 piston, the grooves should be distributed over the end of the piston head. In the latter case, however, there would be more of them at the edge of the piston nearest the 70 place of injection than in the middle.

The grooves are preferably milled into the head of the piston when it is not possible to cast them owing to their small width. If desired, however, they may be made in any 75 other suitable way.

To these ends, the invention consists in the construction, arrangement and combination of parts described hereinafter and pointed out in the claims.

Several illustrative embodiments of the invention are represented by way of example in the accompanying drawing, wherein:

Figure 1 is a section of part of a piston head having grooves according to the present invention,

Fig. 2 shows a modified form of groove, Figs. 3 and 4 show grooves filled with insulating material, Fig. 3 being a vertical section taken on the line 3-3 in Fig. 4, and 90 Fig. 4 a horizontal section on the line 4-4 in Fig. 3;

Fig. 5 is a vertical section showing part of a cylinder containing two pistons and how the grooves are preferably arranged when the 95 fuel is injected approximately parallel to the head of the piston, and

Fig. 6 is a like view showing the arrangement of the grooves when the fuel is injected approximately at right-angles to the 100 piston head.

Referring to these drawings, Fig. 1 shows a portion of a piston having a plurality of very narrow and relatively deep grooves 2 distributed over the surface of the portion 105 5 of the piston which comes into contact with the combustible gases. In the construction shown in Fig. 2, the grooves enlarge toward the interior of the piston in order that the residues of combustion which enter 110

them and act as an insulator of heat cannot fall out.

Instead of the grooves being left to be filled with the residues of combustion they may be filled from the beginning with insulation, but it must of course be possible for the material of the piston left between the grooves to expand. In the arrangement shown in Figs. 3 and 4 insulation 6 has been 10 cast into the head of the piston and has the shape shown in plan view in Fig. 4, expansion of the piston head being possible owing to narrow gaps extending to the layer of insulation. Instead of the insulation being 15 cast in when making the piston, if desired it may be introduced into the grooves after the piston has been cast.

In Fig. 5, a construction is shown consisting of a cylinder having two pistons therein 20 adapted to reciprocate in opposite directions. The fuel is admitted to the space within the cylinder and between the two pistons 25 through inlets or nozzles 3 which inject the fuel in sheets or layers disposed transverse to the axis of the cylinder. In this type of engine, the faces of the two pistons are provided with the deep narrow grooves in their adjacent faces, the grooves having their side walls close together and being either parallel, as shown in Figs. 1, 3 and 5, or substantially parallel but slightly wider at the bottom, as indicated in Fig. 2; preferably the 30 number of grooves is increased over the portion of the two pistons which, when the pistons are close together, lie closest to the adjacent inlets. Fig. 6 shows a cylinder 35 with a single piston reciprocating therein and an inlet valve in the end of the cylinder directed toward the end of the piston. The

deep narrow grooves are provided in the 40 end of the piston and these are preferably arranged closer together at the center.

I claim:—

1. A piston for an internal combustion engine constructed to permit expansion and 45 contraction with changes of temperature without injury by providing a plurality of deep and narrow grooves on the end of the piston which is exposed to the fuel and having said grooves shaped to reduce heat 50 losses by making them so narrow as to substantially prevent movement of the gases of combustion in the grooves when the engine is in operation; substantially as described.

2. A piston for internal combustion engines having a plurality of grooves in the 55 end face of the head thereof, and a liner of insulation in each groove, the free space in each liner being very narrow and relatively 60 deep.

3. A piston for internal combustion engines having a plurality of very narrow, 65 relatively deep grooves in the end face of the head thereof, each groove being filled with insulation, for the purpose specified.

4. A piston for internal combustion engines having a plurality of very narrow, 70 relatively deep grooves in the end face of the head thereof, the grooves being located closest together at that part of the piston head which is exposed to the greatest heat, for the purpose specified.

In testimony whereof I affix my signature in presence of two witnesses.

HUGO JUNKERS.
